CLAIM

The ornamental design for a bear-shaped drinking container, as shown and described.

DESCRIPTION

FIG. 1 is a perspective view of a bear-shaped drinking container, showing my new design;

FIG. 2 is a front view of the bear-shaped drinking container of FIG. 1;

FIG. 3 is a rear view of the bear-shaped drinking container of FIG. 1;

FIG. 4 is a right-side view of the bear-shaped drinking container of FIG. 1;

FIG. 5 is a left-side view of the bear-shaped drinking container of FIG. 1;

FIG. 6 is a top plan view of the bear-shaped drinking container of FIG. 1; and,

FIG. 7 is a bottom plan view of the bear-shaped drinking container of FIG. 1.

(Continued)

The broken lines are for illustrative purposes only and form no part of the claimed design.

1 Claim, 6 Drawing Sheets
